UNITED STATES PATENT OFFICE

FERDINAND E. ENGLISH, OF ST. LOUIS, MISSOURI.

HAT.

1,129,857.

Specification of Letters Patent.

Patented Mar. 2, 1915.

Application filed August 19, 1914. Serial No. 857,536.

To all whom it may concern:

Be it known that I, FERDINAND E. ENGLISH, a citizen of the United States, residing at the city of St. Louis, State of Missouri, have invented a certain new and useful Improvement in Hats, of which the following is a specification, reference being had to the accompanying drawings, forming a part thereof.

10 This invention relates to a certain new and useful improvement in hats and the like.

Due to the fact that both men's and women's hats, as now generally manufactured, 15 are formed or made with a head-size or portion adapted and designed to fit but one certain size of head, the hat merchant or milliner is compelled, under the exigencies of business, to have at hand or in stock to 20 accommodate his trade a more or less large quantity or number of hats all of the same prevailing design or style, but differing in head-size only. Such stocks, particularly in 25 the case of women's and girls' hats, are often expensive and run into money and also require considerable floor or wall space for 30 display or storage. Consequently, so far as I am aware, hats, and especially stiff hats or the like, adapted and designed to inter-changeably fit, within certain limits, 35 changeably neatly fit, within certain limits, various sizes of heads have long been desired, in order that the merchant or milliner might equally well, with a much less stock at hand, take care of and accommodate 40 his trade, thus resulting, among other date his trade, thus resulting, among other advantages, in a reduced expenditure of 45 money and a saving of display or storage space.

The object of my present invention is 40 hence principally to provide a hat having a head-size or head-portion, originally stiff and of a certain fixed size, capable of interchangeably fitting heads of various sizes.

With the above and other objects in view, 45 my present invention resides in the provision in a hat having a stiff head-size or portion, that is to say, a head-size or portion adapted and designed when originally formed and shaped to fit one certain or pre-determined size of head, of a fixed yielding 50 band for adjustably reducing the predetermined size of the head-opening to adapt the hat to interchangeably fit, within certain limits, heads of various sizes.

55 In the accompanying drawings, Figure 1 is an inverted view of a hat embodying my

invention; Fig. 2 is a fragmentary view of the same, the hat being shown in proper position to be worn; Fig. 3 is a fragmentary plan view of the yielding or elastic member or band forming part of my new hat as when detached from, and prior to being fixed in, the head-size of the hat; and Fig. 4 is an enlarged fragmentary view of the hat as seen in Fig. 1.

65 Referring to the said drawings, in which like reference characters refer to like parts throughout the several views, 1 indicates a preferably so-called stiff hat or the like, which may be of any ordinary or preferred 70 form or design and material. This hat 1, as shown, comprises a brim 2, a crown 3, and a head-opening 4. Head-opening 4, or, as I will call it, head portion 4, which is usually, particularly in women's and girls' hats, 75 made of some stiff material, such, for instance, as wire or buckram, and is generally somewhat elliptical in outline in inverted plan view, is, in the trade, commonly known and designated as head-size of the 80 hat, being that part of the hat which is designed to fit the head. Brim 2, crown 3, and head-portion 4 are here shown as integrally forming hat 1, but it will be obvious and readily understood that said parts 85 may be separate members fixed or secured together in any suitable manner to form the hat proper.

Fixed within head-portion 4 preferably 90 at or closely adjacent its lower or outer edge, as seen in Fig. 2, or, as it might be said, at or adjacent the rim or mouth thereof, and extending preferably continuously therearound, is a yielding member or strip 95 5 preferably of elastic webbing or analogous material having any suitable width, yielding member or strip 5 being, by means of thread stitches or the like passed therethrough only at and along its outer side or marginal edge, fixed to and within the head-portion 4 of hat 1, all as clearly shown in 100 Figs. 1, 2, and 4.

In sewing or otherwise securing yielding member or strip 5 in fixed position to and within head-portion 4, strip 5 is first longitudinally or lengthwise stretched and then, while in stretched condition, sewed or otherwise fixed at and along its outer side or marginal edge only, as before stated, to and within the head-portion 4 of the hat. Consequently, in the finished hat, strip 5, while in stretched condition at and throughout 110

outer or fixed marginal portion, is in relatively unstretched condition at and throughout its inner elastically free portion. And consequently also strip 5, in the finished 5 hat, normally assumes a flatwise position at an angle inwardly relatively to the head-portion 4 of the hat, or, as it might be described, is normally flatwise disposed approximately horizontally within the area of 10 the opening of the head-portion 4 of the hat, as clearly seen in Fig. 1, strip 5 thereby yieldingly reducing the predetermined size—interior area—of head-portion 4 and adjustably adapting the same to fit heads of 15 other sizes. On the hat being placed upon a head having a size smaller than, or even substantially the same as, the predetermined size of head-portion 4 of the hat, but larger than the somewhat elliptical opening into 20 the hat provided by strip 5 when in its said normal position strip 5 will yieldingly give inwardly or upwardly at its relatively unstretched inner portion to accommodate said head. At the same time strip 5 will yieldingly engage the head without unduly binding thereupon and serve not only as a soft 25 elastic cushion, so to speak, for the hat upon the head, but also as a retaining or securing member therefor. The hat is thus yieldingly self-securing upon the head, and the use of pins or the like in the case of women's 30 and girls' hats, the use of which, as is well known, is most objectionable and in some sections of the country, as I am informed, 35 is even prohibited, is entirely obviated.

From the foregoing, it will hence be seen that by my invention, through the novel use of simple and inexpensive means, I provide a so-called stiff hat or the like capable of 40 interchangeably neatly fitting heads of various sizes within certain limits depending upon the predetermined size of the head-portion of the hat and the width and elasticity of the yielding strip 5.

45 I am aware that minor changes in the form, construction, arrangement, and combination of the several parts of my new hat may be made and substituted for those herein shown and described without departing 50 from the nature and principle of my invention.

Having thus described my invention, what I claim and desire to secure by Letters Patent is:

55 1. In a hat or the like, a head-portion

adapted to fit a predetermined size of head, and a flat strip of elastic webbing fixed at one side edge only to said head-portion for resiliently reducing the size of said head-portion to yieldingly fit sizes of head smaller than said predetermined size, said strip extending lengthwise around within said head-portion and disposed normally flatwise approximately horizontally within the opening thereof.

2. In a hat or the like, a head-portion adapted to fit a predetermined size of head, and a flat strip of elastic webbing fixed at one side edge only to said head-portion for resiliently reducing the size of said head-portion to yieldingly fit sizes of head smaller than said predetermined size, said strip extending lengthwise around within said head-portion partly in stretched condition and normally partly in relatively unstretched 70 condition and disposed flatwise approximately horizontally within the opening of said head-portion.

3. In a hat or the like, a head-portion adapted to fit a predetermined size of head, and a flat strip of elastic webbing fixed at one side edge only to said head-portion for resiliently reducing the size of said head-portion to yieldingly fit sizes of head smaller than said predetermined size, said strip extending continuously around within said head-portion in stretched condition at and throughout its fixed outer edge and normally in relatively unstretched condition at and throughout its elastically free inner 90 edge and disposed flatwise approximately horizontally within the opening of said head-portion.

4. In a hat or the like, a head-portion, and a strip of elastic webbing of suitable 95 width extending continuously around within said head-portion adjacent the rim thereof, said strip being permanently, while in lengthwise stretched condition, fixed at and only one side edge to said head-portion and being disposed normally flatwise approximately horizontally within the opening thereof.

In testimony whereof, I have signed my name to this specification, in the presence 105 of two subscribing witnesses.

FERDINAND E. ENGLISH.
